MOUNTING DEVICE FOR LIGHTING
FIXTURE LENS

Howard H. Williamson, San Francisco, Calif., assignor to Associated Lighting Service, San Francisco, Calif., a copartnership

Application October 17, 1949, Serial No. 121,667

6 Claims. (Cl. 240—78)

1

This invention relates to lighting fixtures and more particularly to a lighting fixture having a novel support structure for the lens opening and support.

The prior art contains many examples of lighting fixtures, particularly those adapted for ceiling or wall installation, in which various means for obtaining access to the fixture have been shown. Many of these are unsightly or do not provide an efficient means for removing and installing other bulbs and lenses. Others have removable portions which must be held by the user during changing which is unsafe and difficult if he is standing on a step ladder or other support near the ceiling.

The present invention has been designed to overcome these difficulties and to provide a lighting fixture with a removable face or bottom for permitting repair or changing the elements.

One of the objects of the invention is a lighting fixture having a bottom lens support which is adapted to be moved away from the housing and yet supported in the removed position.

Another of the objects of the invention is a lighting fixture having a bottom lens support which may be moved outwardly from the housing and swung away to permit access to the lens, bulb, etc.

A further object of the invention is a lighting fixture having a removable bottom lens support suspended from mechanism located entirely within the housing.

Yet another object of the invention is a lighting fixture having a lens support mechanism entirely located within the housing and accessible through the lens opening.

Still another object of the invention is a lighting fixture having a movable bottom to permit efficient change or removal of bulbs, lenses, etc.

And a still further object of the invention is a latch and support mechanism for a lighting fixture entirely located within the housing.

In the drawings:

Fig. 1 is a side elevation of the preferred form of the device in its position in the ceiling, with the ceiling shown in cross section. The dotted lines indicate the position of the bottom after the same has been lowered and swung away.

Fig. 2 is a top plan view of the device shown in Fig. 1.

Fig. 3 is a bottom plan view of the device shown in Fig. 1.

Fig. 4 is a side elevation of the device shown in Fig. 1, with certain portions cut away to show the construction.

2

Fig. 5 is a sectional view of the device along the lines 5—5 of Fig. 4.

Fig. 6 is a partial top plan view of the device shown in Fig. 1 with certain portions cut away to show the construction.

Figs. 7, 8, and 9 are partial enlarged elevations of the support and latch mechanisms in varying positions.

In general the invention comprises a housing adapted to be seated in a recess in the ceiling. It is provided with a bottom supporting a lens element over a lens opening. The bottom is supported by a mechanism which permits the bottom to be lowered and partially swung away from the housing and which permits the bottom to be removed if desired. The said mechanism is entirely enclosed within the housing and is accessible through the lens opening.

The preferred form of the invention is illustrated in the drawings and is described in detail below. It should, of course, be clearly understood that this form is only one of many, others of which will be obvious to those skilled in the art.

The device comprises a metal housing, generally designated 1. The particular form shown is square, having a top 2 and pairs of opposed side walls 3 which may conveniently be formed with a plurality of holes, as at 4, for purposes of ventilation. A strip of angle iron 5 is secured along the inner edge of each of the side walls for stiffening purposes, with its flange extending outwardly of the wall. These parts are secured together, as may the other sections of the unit, by welding, riveting, bolting, etc.

The housing is closed by a separate bottom, generally designated 6. This bottom is formed in the shape of a square frame and is formed with a square central hole, as at 7, to provide a lens opening. The edges of the frame are slightly formed up, as at 8, to improve the appearance and for strength.

The bottom 6 is also provided with an angle iron strip 9 spaced from each of its edges and positioned to fit within and next to the angle iron band 5 on the housing 1, as may best be seen in Fig. 4.

The bottom is provided with a plurality of guide members 11 secured to the upstanding flange of angle iron 9 for holding the lens, to be described, in place. These members may be formed of a piece of flat flexible metal and are secured to the inner surface of the angle iron 9. Each may be formed with strips 12, 13 which are bent over along horizontal and vertical lines, respectively, to form guides. The lens 14 (which may be an

actual lens, a plain glass plate, a colored plate, or whatever is desired) is adapted to lie on the inner upturned flange 8 of the bottom 6 and across the lens opening, as at 7. It is thus seen that the flanges 13 secure the lens from horizontal motion and the flanges 12 limit upward motion of the lens. However it should be noted that flanges 13 lie well above the lens 14 for a purpose to be described.

The bottom 6 is secured to the housing by a pair of supports, generally designated 21. Each support may be formed from a single flat piece of metal and is bent over at its ends to provide a pair of U-shaped guideways 22, 23 at the top and bottom, respectively. One of its longitudinal edges is also bent at a 90° angle to form a stop 24. Each support is also formed with a longitudinal slot, as at 25, adjacent the edge opposite stop 24. The slot is enlarged at its upper end, as at 26, to permit the support to be slipped over a rivet or pivot 27 mounted in the angle iron 5.

It is thus seen that the bottom 6 is effectively hung from the pivots 27 in the housing by means of supports 21 and is adapted to be swung into the dotted position shown in Fig. 1.

Each support 21 is provided with a latch element 31 which is generally rectangular in shape and has one of its edges bent up to form a stop 32 and for strength. The ends of the latch element are slightly curved and are received by the guides 22, 23. The latch element is also formed with a slot, as at 33, providing cam surfaces to engage pivot 27. This slot is positioned angularly with respect to slot 25 and is enlarged at its upper end, as at 34, to receive the pivot 27. The lower end of slot 33 extends substantially horizontally across the latch element, as at 35. A small tension spring 36 is secured across the latch element and is suitably connected between stop 24 on support 21 and stop 32 on latch element 31.

The operation of the latch element may now be described. When the bottom has been loosened from the housing by swinging the latch 32 so that pin 27 is disengaged from the lower end portion 35 of slot 33, the same may be lowered so that it hangs down below the housing, as shown in Fig. 7 and may be swung to the position shown in the dotted lines of Fig. 1. In this position, the pivot 27 is at the upper end of slots 25, 33 in the support 21 and latch element 31, respectively.

To close the entire unit, the bottom may be moved vertically upwardly, until the support 21 slides to the position shown in Fig. 8. The position of pivot 27 in the slots has caused the latch element to rotate clockwise, as can be seen. As further upward motion continues, and as the spring 36 moves past the pivot 27, its action will cause the latch element to quickly rotate in a counterclockwise direction for assuming the position shown in Fig. 9. When the bottom is moved upwardly against the housing, as shown in Fig. 5, the latch element will snap into the position shown in that figure, with pivot 27 being positioned within the horizontal portion 35 of slot 33. In this position, the unit is locked and the bottom cannot move downwardly.

To open the unit from the closed or latched position of Fig. 5, the lower end of the latch element may be moved to the right (in Fig. 5) and the support 21 and bottom 6 will easily slip downwardly to the position of Fig. 7. This movement of the latch element to unlock the same is easily accomplished manually through the lens opening 7 in bottom 6. It is noted, as can best be seen

in Fig. 4, that upward movement of the lens 14 is limited only by the strips 12 on guide members 11. Thus, the lens 14 may be lifted to that point and the fingers or other tool inserted within the housing to move the latch to permit the bottom to be dropped. Stop 32 on the latch provides a convenient surface to apply the necessary force.

The device is, of course, provided with a suitable connector box 41 which is suitably connected to a conventional socket (not shown). A suitable reflector 42 may be provided inwardly of the housing to reflect the light rays of the bulb 43 downwardly through the lens and lens opening. Normally the unit would be supported in the ceiling of a room, as indicated in Fig. 1 so that the bottom would be flush against both the ceiling and the housing.

It is clear from the above description that the structure permits the changing of bulbs, reflectors, lenses, etc. without completely removing any of the parts. The bottom can be lowered and swung out of the way, as shown in Fig. 1 and it is not necessary for the user to hold anything in his hands while making the necessary changes. Bulbs may be easily changed and by bending up the strips 12 on guide members 11, new or additional lens elements may be inserted. On the other hand, if it is desirable for any reason, the entire bottom and the supports may be removed by slightly shifting the latch element from the position shown in Fig. 7 to obtain coincidence of the enlarged ends 26, 34 of the slots 25, 33, in which position, their flexibility will permit them to be removed from the pivot 27.

It should also be noted that the invention provides an efficient structure for installation inasmuch as only the housing need be originally put in place and the bottom subsequently secured. Also, the latch is entirely contained within the housing and there are no external elements to cause unsightliness and which might be accidentally tripped from outside.

I claim:

1. In a lighting fixture having a housing with an open lower end; a bottom for said housing having a lens therein, an upwardly extending elongated support rigidly secured at its lower end to said bottom, a pivot on said housing on which said support is adapted to be suspended at a point adjacent its upper end, a slot in said support for receiving said pivot to permit upward movement of said bottom toward said lower end, an elongated latch element carried on said support in side by side relationship with the latter and adapted to engage said pivot during said upward movement and for securing said bottom against said lower end, said latch being provided with a longitudinally extending slot for receiving said pivot during said movement, a recess connecting with said slot for receiving said pivot when said bottom is against said lower end, means for swinging said latch about a horizontal axis during upward movement of said bottom toward said lower end whereby said pivot will be received in said recess for so securing said bottom when the latter is against said lower end.

2. In a lighting fixture having a housing with an open lower end; a bottom for said housing having a lens therein, an upwardly extending elongated support secured at its lower end to said bottom and provided with a longitudinally extending slot, an elongated latch element carried by said support in side by side relationship therewith at all times, said latch element

being provided with a longitudinally extending slot and said housing having a fixed pivot extending through the slots of said support and said latch element, spring means operatively connecting said support and said latch element for urging a sidewall of said latch slot against said pivot at all times, said latch slot being provided with an offset portion adjacent its lower end for receiving said pivot when said bottom is in closed position against said open lower end.

3. In a lighting fixture having a housing with an open lower end; a bottom for said housing having a lens therein, an upwardly extending elongated support secured at its lower end to said bottom and provided with a longitudinally extending slot, an elongated latch element carried by said support in side by side relationship therewith at all times, said latch element being provided with a longitudinally extending slot and said housing having a fixed pivot extending through the slots of said support and said latch element, spring means operatively connecting said support and said latch element for urging a sidewall of said latch slot against said pivot at all times, said latch slot being provided with an offset portion adjacent its lower end for receiving said pivot when said bottom is in closed position against said open lower end, said lens being movable upwardly relative to said bottom to provide access to said latch from outside the housing whereby said latch element may be swung against the resistance of said spring means to remove said pivot from said offset portion to permit lowering said bottom from said closed position.

4. In a lighting fixture having a housing with an open lower end; a bottom for said housing having a lens therein, an upwardly extending elongated support secured at its lower end to said bottom and provided with a longitudinally extending slot, an elongated latch element carried by said support in side by side relationship therewith at all times, said latch element being provided with a longitudinally extending slot and said housing having a fixed pivot extending through the slots of said support and said latch element, spring means operatively connecting said support and said latch element for urging a sidewall of said latch slot against said pivot at all times, said latch slot being provided with an offset portion adjacent its lower end for receiving said pivot when said bottom is in closed position against said open lower end, said pivot having an enlarged head for slidably securing said support and said latch element thereto and said support slot and latch slot being enlarged adjacent their upper ends to permit registration of the enlarged portions of said slots with said head to permit removal of said support and latch element from said pivot when said bottom is in open position.

5. In a lighting fixture having a housing with an open lower end and a bottom including a lens for closing said end, a mounting device for such fixture comprising: an elongated vertically extending support adapted to be secured at its lower end to said bottom, and an elongated latch element in side by side relationship with said support, said support and latch element each being provided with a longitudinally extending slot, a pivot pin passing through said slots and adapted

to be secured at one end to said housing adjacent the lower end of the latter, the opposite end of said pin being enlarged for retaining said latch plate against said support to permit said latch plate to oscillate relative to said support, spring means for urging said latch element in a direction transversely of said slots for holding a longitudinal sidewall of said latch slot against said pin, whereby said bottom may be moved vertically toward and away from said open end when said support is secured to said bottom and said pivot pin is secured to said housing, the lower end of said latch slot being provided with an enlargement adapted to receive said pin when said bottom is against said open end, said spring means being positioned at a point intermediate the ends of said support and said latch element for urging the latter to a position with said enlargement engaging said pin.

6. In a lighting fixture having a housing with an open lower end and a bottom including a lens for closing said end, a mounting device for such fixture comprising: an elongated vertically extending support adapted to be secured at its lower end to said bottom, and an elongated latch element in side by side relationship with said support, said support and latch element each being provided with a longitudinally extending slot, a pivot pin passing through said slots and adapted to be secured at one end to said housing adjacent the lower end of the latter, the opposite end of said pin being enlarged for retaining said latch plate against said support to permit said latch plate to oscillate relative to said support, spring means for urging said latch element in a direction transversely of said slots for holding a longitudinal sidewall of said latch slot against said pin, whereby said bottom may be moved vertically toward and away from said open end when said support is secured to said bottom and said pivot pin is secured to said housing, the lower end of said latch slot being provided with an enlargement adapted to receive said pin when said bottom is against said open end, said spring means being positioned at a point intermediate the ends of said support and said latch element for urging the latter to a position with said enlargement engaging said pin, said latch plate being free for oscillatory movement relative to said support upon vertical movement of the latter relative to said pin.
